UNITED STATES PATENT OFFICE.

CARL M. WENDELSTEIN, OF NORTH ATTLEBORO, MASSACHUSETTS, ASSIGNOR TO
BLISS BROTHERS COMPANY, OF ATTLEBORO, MASSACHUSETTS.

VANITY CASE.

Application filed September 17, 1927. Serial No. 220,088.

This invention relates to certain new and useful improvements in vanity cases, and the primary object thereof is to provide a combined handle, finger loop and latch keeper which can be applied to the vanity case as a unit.

A further object of the invention is to provide a vanity case wherein the latter can be easily and conveniently held in position so as to enable use of the mirror, and to further provide a structure wherein the handle has a finger receiving hole so as to enable the case to be carried in closed position either by use of the finger or by attaching a chain thereto.

The invention has further and other objects which will be later set forth and manifested in the course of the following description.

20 In the drawings:—

Figure 1 is a side elevation partly broken away and in section with the case in closed position;

Figure 2 is a top plan view;

25 Figure 3 is a section on line 3—3 of Fig. 1;

Figure 4 is a perspective view showing the case in open position and held in the hand with the mirror in usable position, and

30 Figure 5 is a side elevation of Fig. 4 on a reduced scale.

The case has a body 1 and a cover 2 hinged thereto at 3'. The cover is provided with a latch that has a curved shank 3 and a ball 35 4 on the free end of the shank.

The present invention particularly resides in the provision of a member generally indicated at 5 which member has a base 6 formed to seat on the top edge of the body 1 and which is provided with integral riveting studs 7 whereby the member can be easily applied to the body and rigidly secured thereto. A finger hole 8 is formed in the member 5 so as to either enable the case to be carried by inserting the finger through the hole 8 or by employing the latter as a means of connection to a chain, as may be desired. Beneath the finger hole 8 there is a second hole 9 which serves as a

keeper for the latch 4. The shank 3 of the latch is formed of spring material so that the same may be easily snapped into and out of engagement with the keeper 9 as is apparent. The member 5 may be of various configurations in accordance with the style of the case and is of a length and width so as to afford a firm and substantial finger grip or handle. By referring to Figures 4 and 5, it will be noted that the member 5 provides such substantial handle by means of which the case may be held with the parts in open position and with the mirror 10 of the cover 2 disposed in usable position.

When the parts are in the position of Fig. 5, the cover has its hinged edge seated against the rim of the body 1, whereby the cover is held at an obtuse angle to the body as clearly shown in Fig. 5, thereby disposing the mirror in convenient usable position.

It will therefore be noted from the foregoing that the member 5 functions in a variety of capacities, namely, as a handle for using the mirror with the parts in open position as shown in Figures 4 and 5; as a finger receiving opening for carrying the case in the closed position of Figure 1, and as a keeper for the latch.

The member 5, it will further be noted, constitutes a unit and same may be easily and quickly applied or attached to the case and at the same time provides an ornamental head structure for the case.

Having thus described my invention what I claim as new and desire to secure by Letters Patent is:—

1. In a vanity case, a body, a rigid handle having a finger-receiving opening projecting outwardly from a side of the body, a cover for the body, a mirror on the inside of the cover, and means to hingedly connect the cover to the body at a point opposite to the handle so as to hold the cover when open at an obtuse angle to the plane of the body.

2. In a vanity case, a body, a rigid handle having a finger-receiving opening projecting outwardly from a side of the body, a

cover for the body, a mirror on the inside of the cover, means to hingedly connect the cover to the body at a point opposite to the handle so as to hold the cover when open at an obtuse angle to the plane of the body, and a latch on the cover, said handle having an opening therein to provide a keeper to re-

ceive the latch, the keeper being spaced from the finger-receiving opening by a part of the handle whereby to hold the finger out 10 of contact with the latch.

In testimony whereof I have signed my name to this specification.

CARL M. WENDELSTEIN.
